CLAIM

The ornamental design for a packaging container for beverages, as shown and described.

DESCRIPTION

FIG. 1. is an elevational view of a packaging container for beverages showing our new design, the opposite being the same in appearance;

FIG. 2 is a view looking from the right of FIG. 1, the opposite side being the same in appearance;

FIG. 3 is a top plan view; and

FIG. 4 is a bottom plan view thereof.

FIG.1.

FIG.2.

FIG.3.

FIG.4.
